(57) CLAIM

The ornamental design for a golf club head, as shown and described.

DESCRIPTION

FIG. 1 is a rear perspective view of a golf club head.

FIG. 2 is a front view of the golf club head.

FIG. 3 is a top view of the golf club head.

FIG. 4 is a toe-side view of the golf club head.

FIG. 5 is a heel-side view of the golf club head

FIG. 6 is a rear view of the golf club head.

FIG. 7 is a bottom view of the golf club head.

FIG. 8 is a toe-side perspective view of the rear of the golf club head; and,

FIG. 9 is a cross-section view of the golf club head taken along cross-section line 9 shown in FIG. 3.

The portions of the golf club head depicted in the figures in broken lines form no part of the claimed design. The dot-dash lines in FIGS. 1, 5, 6 and 7 indicate boundaries of the claimed subject matter, and form no part of the claimed design. The cross-section line in FIG. 3 forms no part of the claimed design.
